UNITED STATES PATENT OFFICE

157,027

BUILDING

Michael Mendell Boonin, Upper Darby, Pa.

Application April 5, 1948, Serial No. 145,516

Term of patent 14 years

(Cl. D13—1)

To all whom it may concern:

Be it known that I, Michael Mendell Boonin, a citizen of the United States, residing in Upper Darby, Delaware County, Commonwealth of Pennsylvania, have invented a new, original, and ornamental Design for a Building, of which the following is a specification, reference being had to the accompanying drawings, forming part thereof.

Fig. 1 is a front elevational view of the building showing my novel design.

Fig. 2 is a side elevational view of the same.

Fig. 3 is a section on the line 3—3 Fig. 1.

Fig. 4 is a top plan view thereof.

I claim:

The ornamental design for a building, substantially as shown.

MICHAEL MENDELL BOONIN.
